MATRIX ROLLING MACHINE

William F. Huck, Forest Hills, N. Y.

Application May 6, 1952, Serial No. 286,350

2 Claims. (Cl. 101—12)

This invention relates to machines for the preparation or forming of matrices for printing purposes and commonly referred to in the printing art as matrix rolling machines.

The object of the invention is the provision of an improved matrix rolling machine designed and adapted to eliminate certain limitations and disadvantages prevalent in existing types of matrix rolling machines.

A particular object of the invention is to provide a matrix rolling machine having a dual roller support for the matrix-supporting table that is effective to prevent tilting of the table in its operating movements.

Another object is to provide a matrix rolling machine wherein the entire table is supported and guided by top and bottom pairs of rollers that coact to maintain the table in horizontal alignment while its possible movements sidewise are prevented by lateral guiding rollers.

A further object is to provide a matrix-rolling machine of generally improved design and construction whereby the device will be comparatively simple and durable, as well as convenient, serviceable and efficient in use.

In the preparation of matrices for printing purposes, the material or "flong," as it is commonly called, of which the matrix is composed, is pressed into the printing surfaces of an operative assembly of type clamped in a chase and under a superimposed soft blanket that is engaged by an overhead pressure-applying roller. The chase, with its prearranged type, is supported on a movable table or bed forming a part of a matrix rolling machine. The movable table itself is engaged on its under surface, in accordance with present day practice, by a single bracing or supporting roller that is intended to brace the table as it moves with the flong-covered type beneath the upper or matrix-engaging roller.

The present day practice of bracing the movable table of matrix rolling machines by a single bottom roller, has a serious disadvantage in that the resultant of the comparatively heavy pressure exerted by the upper or overhead matrix-engaging roller, does not pass directly downward, but to one side and principally to that side of the table opposite to its direction of motion. As a consequence of this, the table tends to exert considerable pressure upon the lateral guide rollers on either side of the underneath bracing roller, thereby appreciably deflecting the latter and causing the table to correspondingly drop.

It will be apparent from the above that the guide rollers, as heretofore mentioned, prevalent in existing matrix rolling machines, must yield sufficiently to permit such deflection of the underneath roller without causing excessive wear on the side rollers.

In accordance with an important feature of this invention, the movable table is supported on two rollers which are spaced far enough apart to permit the resultant pressure line to pass centrally between their respective axes. This construction effectively eliminates the tendency of the movable table to tilt as it travels from one side to the other. In conventional machines, the weight of the

2

table tends to incline it downwardly alternately on one side and then on the other side.

As indicated above, the entire table of the machine of this invention is supported solely by two rollers on the bottom, and maintained firmly in its horizontal position therein by two auxiliary marginal rollers on top that hold it firmly against the two main lower rollers. The table, in its reciprocating movements, is guided by two other auxiliary rollers that prevent any deviation from its normal path of parallelism with its longitudinal axis and while in contact with the matrix-engaging roller.

Other objects and advantages residing in the combination and arrangement of parts and in the novel design and construction, will appear as the description proceeds and will be best understood when taken in connection with the accompanying drawings wherein:

Figure 1 is a side elevational view of a preferred form of the invention, showing the matrix-engaging roller in contact with a chase and its type during the process of forming a matrix therefrom;

Fig. 2 is a vertical sectional view, taken on line 2—2 of Figure 1 and as seen in the direction of the arrows;

Fig. 3 is an enlarged, fragmental, sectional detail view, of parts connected to and adjacent the right hand side 25 of the movable table that carries the chase and matrix;

Fig. 4 is an enlarged, transverse, sectional view, taken on line 4—4 of Figure 2, looking in the direction of the arrows;

Fig. 5 is an enlarged, fragmental, elevational view, as 30 seen in the direction of the arrows 5—5 of Figure 4;

Fig. 6 is an elevational view, taken on line 6—6 of Figure 2, but with the movable table and certain other parts removed for clarity of illustration; and showing the means employed for varying the belt tension and consequently the effective engagement of the matrix-engaging roller with the matrix;

Fig. 7 is an enlarged, fragmental, sectional view, taken on line 7—7 of Figure 6, and as seen in the direction of the arrows;

Fig. 8 is an elevational detail view of the means for actuating the limit switches that operate to restrict the travel of the table; and

Fig. 9 is a reduced elevational view of the movable table, pressure cylinder, rollers, matrix and chase, but 45 with the frames and certain other parts removed for clarity of illustration.

In the drawings wherein similar characters of reference indicate corresponding parts in the views, 11 and 12 designate side frames reinforced and connected at their 50 lower ends by braces 13, 14; and at their upper portions by a brace 15 having a flange 15a suitably secured to the said side frames.

The lower ends of the side frames 11, 12 have angle members 11a, 12a, respectively secured thereto. These 55 angle members have adjusting screws, as at 16, resting on base plates 17, 18 in turn seated on the ground or floor. The adjusting screws 16, it will be understood, serve to level the entire machine and provide a compensation for any unevenness of the base support for the machine.

Between the side frames 11, 12 is a motor 19 having its flanges 20 fastened, as by the screws 21, to the side frame 11. The shaft 22 of the motor 19 is provided with a pinion 23 which meshes with a gear 24 keyed to a shaft 65 25 and spaced from the side frame 11 by a washer 26 abutting a bearing 27 secured in the same side frame 11. The gear 24 is removably fastened to the shaft 25 in any suitable manner, as by the screw 28 and washer 29.

The left hand side of the shaft 25, as seen in Figure 2, 70 is shouldered, as at 25a, against which a pinion 30 is normally in abutment, the said pinion also abutting the bearing 27. The pinion 30 is keyed to the shaft 25 and

meshes with a gear 31 fast to a roller 32 rotatably arranged in the side frames 11, 12 and beneath a reciprocating or movable table 33.

The right hand portion of the shaft 25, similarly to the left hand side, has a shoulder, as at 25b, to accommodate a pinion 34 confined between the shoulder 25b and a bearing 35 retained in the side frame 12 by plates 36 bolted to either side of the frame 12. The pinion 34 meshes with a gear 38 fastened to a roller 39 also rotatably arranged in the frames 11 and 12 and beneath the movable table 33. The rollers 32 and 39, as indicated above, are in contact with the under side of the table 33 that is movably supported or braced thereby.

The gears 31 and 38 mesh with racks 40, 41 fastened in spaced parallel relation to the bottom of the movable table 33. When the gears 31 and 38 are rotated through the intermediary of the motor 19 and via the chain of gears described above, it will be understood that the table 33 will be moved backwardly or forwardly in accordance with the direction of rotation of the said gears 31, 38.

A pulley 41a is fastened to the outer end of the shaft 25 and spaced from the adjacent side frame 12 by a washer 41b. The pulley 41a is operatively connected to and drives frictionally an upper matrix-engaging roller or cylinder, as hereinafter described.

The movable table 33 is guided in its reciprocating movements between the side frames 11 and 12 by guide rollers 42, 43 retained in the said side frames and engaging the lateral edges of the table. The latter is normally pressed downwardly to a variable degree by pressure rollers 44, 45 engaging its marginal portions and mounted on eccentric studs 46, 47 adjustably secured in the side frames 11, 12. By turning the said eccentric studs 46, 47, it will be understood the pressure rollers 44, 45 may be moved about the eccentric axes of the studs 46, 47 and thereby be effective to regulate the marginal pressure on the movable table 33 to the desired degree.

Between the upper portions of the side frames 11, 12 a matrix-engaging upper cylinder or roller 48 is arranged that serves to apply pressure frictionally or tangentially to the matrix material resting on the type (not shown) locked in the chase "C" located on the movable table 33. The right hand end of the matrix-engaging cylinder 48 has secured thereto a pulley 48a connected to the lower pulley 41a by a belt 48b. When the shaft 25 is driven by motor 19, the matrix-engaging cylinder 48 will be rotated at a preferred somewhat greater speed than that of the movable table 33.

The matrix-engaging cylinder 48 has its journals 49, 50 turnably received in bearings 51, 52 secured in eccentric bearing boxes 53, 54. The bearings 51, 52 are removably retained in the said bearing boxes by inner and outer plates 55, 56 respectively. The inner plates 55, as best shown in Figure 2, are bolted to flanges 55a formed on an adjustable tubular brace 57.

The circular wall of the tubular brace 57 is slotted, as at 57a, to accommodate a manually-operable shaft 58 having a threaded portion 58a that is engaged by threads in an arm 59 and in a nut 60. The arm 59 and nut 60 are prevented from rotating by projections, as at 61, on pivot pieces 61a.

The shaft 58 may be turned by means of hand-wheels, as at 62. The threaded portion 58a of the adjustable shaft 58, it will be understood, serves to move the arm 59 and nut 60, both of which engage the pivot pieces 61a that in turn engage the tubular brace 57. When the brace 57 is moved, the inner plates 55 fastened thereto and to the eccentric bearing boxes 53, 54 mentioned above, will angularly move the latter and thus increase or decrease the distance of the matrix-engaging roller 48 relatively to the movable table 33.

The means for varying the effective driving pressure of the matrix-engaging roller 48 comprises a shaft 63

turnably supported in bearing brackets 64, 65 fastened to the side frame 12. The shaft 63 is provided with right and left hand threaded portions 63a, 63b engaged in correspondingly threaded elements or nuts 66, 67 that are prevented from rotating by guides, as at 68, 68a fastened to the side frame 12. The outer ends of the shaft 63 are engaged by adjusting collars 69, 70 keyed thereto and fastened by nuts, as at 71.

Coil springs 72, 73 arranged respectively on the right hand and left hand threaded portions 63a, 63b of the shaft 63 are confined between the nuts 66, 67 and the collars 74, 75 respectively. The outer sides of the collars 74, 75 are in abutment with a pair of levers or arms 76, 77 (Figure 2) arranged in spaced relation and having their upper ends bifurcated, as at 77a, to freely accommodate the body portion of the shaft 63.

The hubs of the lever arms 76, 77 are turnably mounted on studs, as at 78, fastened to the side frame 12. The lever arms 76, 77 have turnably mounted thereon, as by the studs 79, 80 idler pulleys 81, 82 that, as best shown in Figure 6, are engaged by the belt 48b that serves to drive the pressure roller 48 via the pulley 48a.

The desired adjustment or tensioning of the belt 48b is effected by moving the two idler pulleys 81, 82 that are normally in engagement with the said belt. This is accomplished by turning the adjusting collars 69, 70 thereby causing the nuts or threaded elements 66, 67 to variably compress or relieve the coil springs 72, 73 engaged against collars 74, 75 thus angling or turning the lever arms 76, 77 that carry the above-mentioned idler pulleys. Inspection of Figure 6 will show the effect caused by bodily moving the two idler pulleys relatively to the engaged belt 48b. It is to be noted that pulley 41a, belt 48b, idler pulleys 81, 82 and the matrix-engaging cylinder 48 constitute a flexible drive assembly that is designed and adapted to frictionally drive the said matrix-engaging cylinder 48 at a somewhat greater surface speed than that of the traveling table. The pressure cylinder 48 itself is adapted to frictionally and tangentially engage the matrix-forming material on the table 33 and assume the different surface speeds the latter may acquire.

Indicating means to denote the extent of the movement or adjustment of the matrix-engaging cylinder 48 with respect to the table 33 includes an endless calibrated tape 83 supported on two reels 84, 84a rotatably mounted on studs, as at 85, fastened to the top brace 15. The tape 83 passes through a slot 59a in the arm 59 and is retained to the latter by clamps, as at 86.

When either of the two hand-wheels 62 is turned to rotate the shaft 58 in order to move the arm 59 and nut 60 and therefore brace 57, the eccentric bearing boxes 53, 54 attached to the latter will bodily move the matrix-engaging roller 48 towards or away from the table 33, thus varying the tangential and/or frictional pressure to be applied to the type with its matrix.

The movement of the calibrated tape 83 as it moves with the arm 59 and consequently of the upper cylinder 48, may be shown by an indicating needle 87 fastened to the brace 15 and denoting the markings of the said tape as seen through a sight-glass 87a, in order to show the actual movement of the matrix-engaging cylinder 48.

When the shaft 22 of the motor 19 rotates, the matrix-engaging cylinder 48, as mentioned above, will rotate at a surface speed somewhat greater than that of the table and of the material thereon and, by virtue of the flexible drive assembly, may assume the different surface speeds of the said material when it engages same. The motor 19 is controlled from a push-button station 87b that may be operated to start the movement of the table 33 in either direction within limits defined by two limit switches 88, 89, as follows:

Attached to either of the opposite ends of the table 33 are two abutments or stops, one of which is illustrated, as at 91. These stops are adapted to be alternately en-

gaged by a pair of bell crank levers 92, 93 fastened to a rock shaft 94 having lever arms 95, 96 attached thereon. The lever arm 95 is engageable by a limit switch 88, while lever arm 96 is adapted to engage the other limit switch 89.

When one of the push-buttons of the station 87b is operated, the motor 19 will be energized through an electric circuit (not shown) and the table 33 will travel until one of the abutments, for example abutment 91 is contacted by the bell crank lever 92, thus stopping the table by breaking the electric circuit to the motor 19 via the limit switch 89 through the intermediary of the lever arm 96. The table 33 may now be reversed by operating the other push-button of the station 87, in which event the other abutment (not shown) will be engaged by bell crank lever 93 thus moving lever arm 95 to operate limit switch 88. The application of the matrix-engaging cylinder 48 to the flong-covered type in the chase "C," as the table 33 moves thereunder, has been indicated above.

Figure 9 illustrates the manner in which the resultant pressure line from the upper matrix-engaging cylinder 48 passes downwardly and to the left in the direction of line "a" as the table 33 with chase "C" and matrix "m" moves in the direction indicated by arrow "a'." The resultant pressure line will have the direction shown by line "b" when the table moves in the direction of arrow "b'." It will be noted that the pressure line always remains between contact points "p" and "p'." As mentioned above, this construction forms a salient feature of the invention since, in combination with the other coacting components, it assures the fabrication of an accurate matrix.

It is to be understood that the invention may be embodied in other specific forms without departing from the spirit or essential attributes thereof, and it is accordingly desired that the present embodiment be considered in all respects as illustrative and not restrictive, reference being had to the appended claims rather than to the foregoing description, to indicate the scope of the invention.

What I claim is:

1. In a matrix-rolling machine of the kind described, 40 in combination, a frame, a table movably mounted in the frame and having rack means secured thereto, a pair of rollers arranged in the frame and engaging the under side of the table, said rollers having gears fastened thereto, said gears engaging the rack means, a pressure cylinder rotatably mounted in the frame, said pressure cylinder having its longitudinal axis arranged in a plane parallel to and centrally between the longitudinal axes of said pair of

rollers, a motor connected to the frame and having a gear, gear and shaft means mechanically connected to and associating the gear on the motor with the gears on the pair of rollers, a friction-belt assembly supported on the frame and mechanically connected to the motor and the pressure cylinder, a pair of stop members fastened to the ends of the table, and lever means engageable by said stop members, said lever means being mechanically connectible to limit switches, each of said limit switches when engaged by said stops, being effective to deenergize the motor and thereby stop movement of the said table.

2. In a matrix-rolling machine of the kind described, in combination, a frame, a table movably mounted in the frame and having rack means secured thereto, a pair of rollers arranged in the frame and engaging the under side of the table, said rollers having gears fastened thereto, said gears engaging the rack means, a pressure cylinder rotatably mounted in the frame and over the said table, said pressure cylinder having its longitudinal axis arranged in a plane parallel to and centrally between the longitudinal axes of said pair of rollers, a motor connected to the frame and having a gear, gear and shaft means mechanically connected to and associating the gear on the motor with the gears on the pair of rollers, a friction-belt assembly supported on the frame and mechanically connected to the motor and the pressure cylinder, adjustable eccentric bearing boxes arranged on the frame and rotatably supporting said pressure cylinder, a plurality of eccentric studs adjustably mounted in the frame, and a plurality of pressure rollers rotatably mounted on said studs and normally engaging marginal portions of the table.
